ATTORNEYS.

UNITED STATES PATENT OFFICE.

EDWIN W. WILSMAN, OF GREEN BAY, WISCONSIN.

BLOTTER HOLDER.

Application filed June 30, 1922. Serial No. 572,047.

To all whom it may concern:

Be it known that I, EDWIN W. WILSMAN, a citizen of the United States, residing at Green Bay, in the county of Brown and 5 State of Wisconsin, have invented certain new and useful Improvements in Blotter Holders, of which the following is a specification.

The invention relates to a blotter holder, and more particularly to the class of hand 10 blotter holders.

The primary object of the invention is the provision of a holder of this character, wherein a sheet of blotting paper can be conveniently clamped in the holder, which may 15 be readily manipulated by the hand of a user for blotting ink, when writing with the latter, the holder being of novel form, so that it can be actuated for the placing of blotting sheets therein for use or the removal of such sheets when new or fresh ones 20 are to be substituted.

Another object of the invention is the provision of a holder of this character, wherein the body of the same has removably fitted 25 thereon a clamping plate, which is secured in place through the medium of rotatable latches, the clamping plate being designed to secure the blotting paper in position on the body for use.

30 A further object of the invention is the provision of a holder of this character, which is extremely simple in construction, strong, durable, thoroughly reliable and efficient in its purpose, novel in construction, and inexpensive in manufacture.

With these and other objects in view the invention consists in the features of construction, combination and arrangement of parts as will be hereinafter fully described, illustrated in the accompanying drawing, and 40 pointed out in the claim hereunto appended.

In the accompanying drawing:

Figure 1, is a side elevation of the holder constructed in accordance with the invention.

Figure 2, is a top plan view thereof.

Figure 3, is a sectional view on the line 3—3 of Figure 1, looking in the direction of the arrows.

50 Similar reference characters indicate corresponding parts throughout the several views in the drawing.

Referring to the drawing, in detail, A, designates generally the body portion of 55 the holder, preferably made from wood, al-

though it may be made from any other material, and is formed with a rounded bottom 5, constituting a rocker surface, over which is adapted to be placed the blotting sheet 6, while the top of said body is flat at 7, the 60 sheet 6, at the ends 8, being turned over the top 7, for a purpose presently described.

Mounted centrally of the body A, on its top 7, and disposed longitudinally for a distance thereof is a rib 9, which may be integral with the body as shown, or made separate therefrom, and adapted to be superimposed upon the top 7, is a clamping plate 10, having a central slot 11, corresponding to the rib 9, for accommodating the latter, and in this manner the clamping plate 10, is held against displacement on the body, the plate being adapted to overlap the ends 8, of the blotting sheet 6, so that the latter will be firmly held over the rounded bottom 5, 75 of the body and maintained smooth thereon.

Secured in the rib 9, are spaced fasteners 12, which mount thereon a handle 13, while between the rib and the handle are turn latches or keepers 14, the same being rotatably fitted on the fasteners, which also serve to hold said latches or keepers as a part of the rib 9 and handle 13, as will be clearly apparent.

The latches 14, are adapted to be turned 85 cross-wise of the plate 10, as shown in Figure 2, of the drawing, to make it fast upon the top of the body A, and thereby hold the ends 8, of the blotting sheet 6, as will appear in Figure 1, of the drawing.

To remove the blotting sheet 6, the turn latches or keepers 14, are moved in a position longitudinally of the body parallel with the rib 9, thereupon the plate 10, can be readily lifted from the top 7, of the body A, and the blotting sheet removed from the latter, as will be apparent.

What is claimed is:

A holder of the character described, comprising a body having a rounded bottom and flat top, a center rib on the top, a plate removably fitted upon the top and having an opening for receiving the rib, a handle rising from the rib, and turn latches between the handle and rib for fastening the plate on the 100 top.

In testimony whereof, I affix my signature.

EDWIN W. WILSMAN.
